United States Patent

Des. 240,636
Patented July 20, 1976

240,636

ENCAPSULATED VACUUM SWITCH

Harold Dennis Haubein, Centralia, Mo., assignor to
A. B. Chance Company, Centralia, Mo.

Filed Mar. 28, 1975, Ser. No. 563,141

Term of patent 14 years

Int. Cl. D13—03

U.S. Cl. D26—13 R

Fig.1.
Fig.2.

FIG. 1 is a perspective view of an encapsulated vacuum switch showing my design;

FIG. 2 is an end elevational view thereof as seen from the end remote from the foreground illustrated in FIG. 1;

FIG. 3 is a top plan view thereof; and

FIG. 4 is a bottom plan view thereof.

I claim:

The ornamental design for an encapsulated vacuum switch, as shown.
